John P. Farbox
ATTORNEY

UNITED STATES PATENT OFFICE

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA

METHOD OF AND APPARATUS FOR APPLYING FLEXIBLE COVERING TO PANEL SURFACES

Application filed December 27, 1929. Serial No. 416,990.

My invention relates to a process and apparatus for smoothly applying a flexible covering to panel surfaces, and more particularly for applying a flexible covering to a panel surface, such as a metal panel for automobile bodies, which has a surface other than a plane surface.

It has heretofore been the practice to apply flexible fabric coverings to such surfaces by applying the fabric to the panel in a wet state, wet from the liquid adhesive applied thereto, and to then press the fabric firmly in contact with the surface by a wooden form contoured to match the surface of the panel to be treated. This had the defect that the form and panel were hard to match up and if matched up, any slight irregularity in either, or the lodgement of a foreign body between them, would result in an imperfect fit between the panel and the wooden form, with the result that the covering was not at all points pressed against the surface, or pressed but lightly so that when the adhesive dried it would not adhere to the panel at these points.

It is a main object of my invention to provide a process and apparatus for applying a flexible cover to such panel surfaces uniformly throughout, so that a superior article of manufacture results, and to do this expeditiously and at small cost.

I attain this object of my invention by the use of an expandible member adapted to exert substantially uniform pressure on the surface to be treated throughout its extent and to so confine the said member as to cause it to exert such pressure to press the flexible cover firmly against all parts of the surface to be covered, and, if desired, to maintain it under pressure, until the adhesive applied to said parts to be united has had time to dry or otherwise cause them to permanently adhere.

Other and further objects and advantages will become apparent from the following detailed description when read in connection with the accompanying drawings.

In the drawings, I have illustrated more or less diagrammatically an apparatus by the use of which my method may be practiced.

Fig. 1 shows a sheet metal panel of irregular surface contour, such as may be conveniently covered by the use of my invention.

Fig. 2 shows a form of my apparatus adapted to treat a plurality of articles simultaneously, the articles being shown in position for treatment, but with the expandible members in collapsed condition.

Fig. 3 is a view similar to Fig. 2, but showing the expandible members expanded to press the covers uniformly against the panels.

In the form of the apparatus shown in the drawings, I provide for the simultaneous treatment of a plurality of articles.

Such apparatus may consist of a box-like structure, designated 10, having closed top, bottom, rear and end walls. The box is divided by a plurality of horizontal partitions 11 corresponding to the number of articles to be simultaneously treated and in its front wall are provided slots 12, one for each compartment as 13 formed by the partitions and the walls of the box. The slots are of a width sufficient only for the convenient placing of the panels to be treated within the compartments and their removal therefrom.

The slots are in the present embodiment of the invention located medially of the front walls of the compartments.

In each of the compartments 13, are placed two expandible bags 14, 15 made of rubber or the like, which conform roughly to the dimensions of the upper and lower halves of the compartments and are confined by the walls thereof. These bags, when collapsed as shown in Fig. 2, are spaced from each other, and when in this condition, they permit the insertion or removal of the articles through the slots 12. It is understood, of course, that slots like slots 12 could be provided in the rear wall of the box 10 which would permit the feeding of the articles in one side and out the other.

Each of the bags 14, 15 is connected by a short pipe 16 with a manifold 17 which can be placed in communication with a source of compressed fluid, such as compressed air by the valve, represented at 18. This valve may be provided with a suitable exhaust port, when turned to shut off the air supply or

otherwise to permit the air to exhaust from the bags.

In the form of my invention shown, it will be obvious that when the air is admitted to the bags 14, 15, they will be expanded and will press against the surface of an article placed between them with a substantially uniform pressure throughout.

The method of my invention is carried out by the use of my apparatus in the following manner. A panel A is taken and the flexible cover, as fabric B previously wet with an adhesive material, such as glue, is placed against the surface or surfaces thereof which it is desired to cover. It is then passed through the slot 12 between two deflated bags 14 and 15 as shown in Fig. 2. Similarly each of the remaining compartments may be similarly filled. The compressed air is then turned on through the operation of valve 18 and the bags 14 and 15 are expanded under a definite pressure which is applied uniformly throughout and consequently presses all parts of the flexible cover or covers firmly into contact with all parts of the surface which it is desired to cover, so that the covering will conform to every irregularity of said surface and adhere thereto. My method further comprehends, maintaining the articles in the apparatus, under such pressure, or a reduced pressure, if desired, until the adhesive material, such as glue, has dried sufficiently to insure that no part of the covering will break away from the panel surface to which it is applied, after the pressure is released by the deflation of the bags.

By this comparatively simple method and apparatus I am enabled to produce a smoother article and one in which the covering is more firmly applied than has been possible by the methods heretofore used. It is also a very economical method of covering such articles.

While I have herein shown and described a specific apparatus for carrying out my improved method, it will be understood that changes and modifications may be made within the skill of the mechanic, without departing from the spirit and scope of the invention as expressed in the claims appended hereto.

What I claim is:—

1. The method of applying a flexible covering to an irregularly-surfaced panel which consists in bringing a fabric treated with an adhesive agent to cover the face of the panel to be treated, and then simultaneously applying a substantially uniform pressure to all the parts of the fabric to be applied to press it into contact with the irregular face of the panel throughout.

2. The method of applying a flexible covering to an irregularly-surfaced panel which consists in treating the covering with an adhesive agent and applying it to the panel with said agent in wet condition, then simul-

taneously pressing the covering into contact with the irregular face of the panel through the surface to be treated, and maintaining it under pressure until the adhesive agent had dried sufficiently to cause the covering to adhere to the surface.

3. An apparatus for applying a flexible cover to a panel surface comprising opposed pockets adapted to receive the panel between them, and expandable bags in said pockets adapted when expanded to exert a substantially uniform pressure upon said panel surface.

4. An apparatus for applying a flexible cover to a panel surface comprising a support for the panel, a backing opposed to said support, and an expandable bag supported by said backing and adapted to be expanded, and fluid means for expanding said bag to press it against the surface to be treated with a substantially uniform pressure throughout.

5. An apparatus for applying flexible covers to panel surfaces comprising a tier of shelves forming recesses therebetween to receive the articles to be treated, each of said shelves being provided with at least one expandable bag, said bags being each connected to a fluid pressure supply, whereby they may be simultaneously expanded to press them into contact with the articles to be treated throughout.

In testimony whereof I hereunto affix my signature.

JOSEPH LEDWINKA.
